Des. 238,279
Patented Dec. 30, 1975

238,279

DENTAL FLOSS HOLDER

Jerome J. French, 1410 Hoffman Ave.,
Park Ridge, Ill. 60068

Filed Mar. 12, 1975, Ser. No. 557,737

Term of patent 14 years

Int. Cl. D24—99

U.S. Cl. D24—1 D

FIG. 1 is a top perspective view of a dental floss holder showing my new design;

FIG. 2 is a bottom perspective view thereof;

FIG. 3 is a side elevation thereof;

FIG. 4 is an end elevation thereof;

FIG. 5 is a top plan view thereof;

FIG. 6 is a side elevation thereof;

FIG. 7 is an end elevation as seen from the side opposite FIG. 4; and

FIG. 8 is a bottom plan view thereof.

I claim:

The ornamental design for a dental floss holder, as shown.
